UNITED STATES PATENT OFFICE

91,820

DESIGN FOR A VANITY MAKE-UP MIRROR

Lurelle Guild, Darien, Conn., assignor to C. F. Church Mfg. Co., Holyoke, Mass., a corporation of Massachusetts

Application August 26, 1933, Serial No. 49,142

Term of patent 7 years

all whom it may concern:

Be it known that I, LURELLE GUILD, a citizen of the United States, residing at Darien, in the County of Fairfield and State of Connecticut, have invented a new, original and ornamental design for Vanity Make-up Mirror, of which the following is a specification, reference being had to the accompanying drawing, forming part hereof.

Fig. 1 is a front elevation of a mirror showing my new design; and

Fig. 2 is a side elevation of the same mirror.

I claim:

The ornamental design for a vanity make-up mirror substantially as shown.

LURELLE GUILD.
